Primary Examiner — Susan Bennet Hattan*Assistant Examiner* — Leanne Was(57) **CLAIM**

The ornamental design for a video camera dock, as shown and described.

DESCRIPTION

FIG. 1 is a front, side, and top perspective view of a video camera dock embodying the new design.

FIG. 2 is a back, side, and bottom perspective view thereof.

FIG. 3 is a front view thereof.

FIG. 4 is a back view thereof.

FIG. 5 is a right side view thereof, the left side view being a mirror image.

FIG. 6 is a top view thereof; and,

FIG. 7 is a bottom view thereof.

The dash-dot-dash lines represent the boundary of the claimed design. The uniform repeating broken lines depict portions of the video camera dock that form no part of the claimed design.

1 Claim, 4 Drawing Sheets(56)
